UNITED STATES PATENT OFFICE.

KARL BERGSTROM, OF BERTHIERVILLE, QUEBEC, CANADA.

MATCH-BOX-FILLING MACHINE.

Application filed June 10, 1927. Serial No. 197,952.

The present invention relates to container filling machines and more particularly to a machine adapted for filling match boxes and like containers.

- 5 An important object of the invention is to provide a machine of relatively simple construction and mode of operation which may be employed for the filling of match containers in a rapid and effective manner.
- 10 A further object of the invention is the provision of a machine of the above character which will arrange the matches in the containers in reverse positions so that one layer will be arranged with their heads disposed at one end of the box, while a second superimposed layer of the filler will be disposed with the heads at the opposed end.

Another object of the invention is the provision of a machine embodying a magazine to which the empty containers are delivered in successive series and, after the filling, removed to a take-off position.

Still another object of the invention is the provision of a machine of the above type embodied with mechanism by means of which the material in the magazine is constantly agitated to permit the articles to be freely deposited in the containers.

Still another object of the invention is the provision of mechanism wherein a series of containers will be simultaneously filled in timed sequence.

Other objects and advantages of the invention will become apparent as the description progresses.

In the accompanying drawings forming a part of this specification and in which like reference characters are employed to designate corresponding parts throughout the same:

Figure 1 is a top plan view of a machine constructed in accordance with my invention.

Figure 2 is a side elevation partly in section.

Figure 3 is an end elevational view.

Figure 4 is a fragmentary side elevational view of the magazine releasing mechanism.

Figure 5 is a horizontal sectional view taken on the line 5-5 of Figure 4.

Figure 6 is a vertical sectional view showing the mechanism employed to reversibly rotate the containers.

Figure 7 is a detail view of the container elevating mechanism.

Figure 8 is a side elevational view of the material agitating means.

Figure 9 is an end elevational view of the same.

Figure 10 is an enlarged transverse section through the filling and converging structure of the machine, and

Figure 11 is a diagrammatic illustration of the principle of operation.

Referring to the drawings, wherein for the purpose of illustration is shown a preferred embodiment of my invention, the numeral 20 generally designates the support frame of the machine embodying a horizontal flat top table 21, longitudinally elongated and supported on vertical standards 22 secured to the ends of the table. Suspended from the underside of the table adjacent the ends are vertically aligned bearing hangers 23 formed with aligned shaft bearings 24 at their lower ends.

Removably supported in elevated position on the table is a magazine embodying a longitudinally elongated casing 25 open at its top and outer side and provided with a pair of laterally extending brackets 26 slidably engageable with a pair of vertical standards 27. Attached to the open side of the casing, at its lower end, is a vertical removable plate 28 adapted to form a suitable magazine for a quantity of matches.

Pivots supported in the lower portion of the magazine casing and disposed in substantially vertical positions are a plurality, in the present embodiment three, uniformly spaced arms 29 connected with stationary pivots 30 projecting through their intermediate portions and adapted to be oscillated thereon. The lower ends of the arms 29 are pivotally connected with a horizontal longitudinal bar 31 shown to advantage in Figure 8. The bar 31 is connected to a rocker mechanism including a horizontal rod 32 rotatably mounted on a bearing 33. A connecting rod 34 is fixed to one end of the rod 32 and pivotally connected with the end of the bar 31. The auxiliary rod 35 is fixed to the opposed end of the rod 32 and carries a rotatable cam engaging collar 36 at its lower end adapted to form a cam follower.

for oscillating the rocker structure and the arms 29 to constantly agitate the matches in the magazine.

Slidably associated with the bottom of the magazine and adapted to form a bottom plate therefor is a longitudinal horizontal plate 37 formed at intervals with transversely extending slots immediately below the connection of the agitating arms 29.

10 This plate is formed with a plurality of, in the present instance four, regularly spaced recesses 38 of rectangular formation adapted to carry a predetermined quantity of material.

15 Rigidly secured to the rear side of the magazine plate 37 and projecting transversely therefrom are a pair of guide rods 39 slidably mounted in horizontal bearings 40 secured upon the table 21. The plate is 20 adapted to be intermittently reciprocated from a retracted position wherein the recesses 38 will be disposed immediately below and register with the bottom opening of the magazine, to a laterally projected position 25 wherein the pockets or recesses 38 will be disposed laterally forward of the magazine as viewed in Figure 10.

To effect reciprocable movement of the magazine plate 37 a link 41 is pivotally connected with apertured lugs 42 formed on the rear central portion of the plate and with a downwardly extending bar 43 adapted to engage a suitable operating cam.

Slidably connected with the bottom surface of the plate 37 are complementary co-acting delivery control plates 44 normally arranged in adjacent closure positions to prevent the delivery of the matches through the pockets and intermittently slidable to separated open positions to permit the matches to drop from the recesses 38 into a suitable container. These plates are formed with transverse flanges 45 depending from their inner edges. The slidable delivery plates 44 are automatically operated at predetermined periods by means of links 46 and 47 connected with the end of the inner and outer plates respectively and with the ends of a rocker bar 48 fulcrumed upon a stationary pivot. Pivotally connected with the lower end of the rocker bar 48 and extending rearwardly through a bearing 49 is a control rod 50 on the rear end of which is threaded a nut 51. As the magazine plate 55 is slidably actuated from an outward retracted position to an inward extended position, the control rod is slidably moved through the bearing 49 until the nut 51 engages the bearing. At this position, the rocker 48 will be swung from its normal position wherein the delivery plates 44 are in closing formation, to its reverse position wherein plates 44 are separated for the delivery of the matches.

65 In order to retard the gravitational move-

ment of the heavier head ends of the matches as they are deposited in the recesses or pockets 38, a relatively thin rigid strip 52 is slidably connected to the bottom edge of the magazine casing as shown in Figure 10, this strip being adapted for transverse sliding movement. The inner edge of the strip is formed adjacent its ends with projections 53 carrying vertical upwardly projecting pins 54. These pins engage the slotted ends of trip-levers 55 fulcrumed intermediate their ends upon pivots 56 supported by brackets 57. The opposite end of each trip-lever is formed with a projection arranged to periodically engage a pair of spaced stationary lugs 58 for slidable operation of the strip. During the final movement of the magazine plate 37 from retracted to extended container filling position, the trip-levers 55 will engage the inner lugs 58 thereby swinging the opposed end of the lever inwardly to laterally actuate the match retarding strip 52 sufficiently to clear the heads of the matches and permit the same to drop into the pockets 38.

Rotatably mounted on the table in longitudinally aligned positions at one side of the magazine are a series of receivers 59 corresponding to the pockets of the magazine plate. These receivers are in the form of inverted U-shaped members of elongated structure, the outer sides of the vertical end pieces being rounded to facilitate the rotary movement thereof. In order that the receivers may be alternately oscillated in semi-circular rotary movement and vertically reciprocated, vertical stems 60 are secured to the lower surfaces adapted for reciprocating and rotary movement in sleeves 61 depending from the table. The upper ends of the stems 60 are formed with enlarged shoulders 62 disposed immediately below the receivers normally seated in counterbores formed in the table. With particular reference to Figures 1 and 10, it will be noted that the receivers 59 are positioned so as to vertically register with the delivery pockets 38 when the magazine plate 27 is in extended delivery position.

Keyed to the lower portions of the stems 60 are annular spur gears 63 held against displacement by enlarged semi-spherical heads 64 formed at the lower ends of the stems. These gears mesh with a longitudinally extending rack 65 simultaneously engaging each spur gear of the series.

The rack is mounted for longitudinal reciprocating movement in spaced bearings 66 depending from the table and is intermittently reciprocated in the bearings by means of a fulcrumed lever 67 pivotally connected with the intermediate portion of the rack while its opposed end is connected with a stationary vertical pivot 68 supported on the inner end of an arm 69. The intermediate

portion of the lever 67 carries a downwardly depending roll 70 engageable with a suitable actuating cam which will be described hereinafter.

- 5 The receivers 59 are liftable periodically in simultaneous series by mechanism including a longitudinal stationary bearing shaft 71 secured in horizontal position below the table upon which are mounted a plurality 10 of tapered lifting arms 72. The inner ends of the arms are rigidly connected to the shaft while the outer ends are formed with pads 73 engageable with the heads 64 of the receiver stems. The shaft 71 is oscillated periodically by means of a lever 74 the outer end of which carries a cam roll 75 engageable with an operating cam.

15 The driving mechanism will next be described with reference to Figures 2 and 3 20 wherein is illustrated a transversely extending main drive shaft 76 journaled in bearings 77 formed on the forward frame standards 22. Keyed on one end of this shaft is a pulley 78 adapted to be continuously driven from any suitable source of power. Fixed on the outer end of the shaft 76 is a relatively large hand wheel 79 operable to manually actuate the mechanism and also serving as a fly-wheel adapted to equalize 30 by its inertia the speed of the parts driven from the shaft.

25 Fixed on the intermediate portion of the drive shaft is a drive pinion 80 on the outer edge of which is secured a drive sprocket. 35 Mounted loosely on the drive shaft in a spaced position with respect to the pinion 80 is a complementary pinion 81 formed with an outwardly extending sleeve 82 carrying a drive sprocket.

40 Journaled in the depending shaft bearings 24 is a longitudinal cam shaft 83 having a relatively large beveled gear 84 fixed on its forward end meshing with the drive pinion 80 and the loosely rotatable pinion 45 81. Thus, the cam shaft is positively driven by the pinion 80 and forms a transmission gear for the rotatable operation of the loose pinion.

45 Supported in elevated position on the forward standards 22 is a transverse auxiliary shaft 85 journaled in bearings 86 fixed to the outer sides of the standards. Rotatably positioned on this shaft at its intermediate substantially central position is a relatively large gear 87 adapted to drive a 50 continuous conveyor. This gear is formed with a laterally extending sleeve 88 which carries a sprocket at its outer end arranged in a vertical plane with the sprocket carried by the drive pinion 80 and connected for simultaneous operation by a chain 89. Loosely mounted adjacent one end of the auxiliary shaft 85 is a second conveyor drive gear 90 formed with a central annular

groove in its periphery. Attached to one 65 side of the gear 90, is a drive sprocket arranged in a complementary position with respect to the sprocket carried by the sleeve 82 and connected by a drive chain 91 so that the gear 90 is rotated with the pinion 70 75 and sprocket carried thereby. As illustrated in Figure 2, the grooved gear wheel 90 is formed with a radially projecting lug 92 adapted to intermittently engage the continuous conveyor.

75 Trained over the gear 87 and a corresponding gear rotatably mounted on the opposite end of the frame is a continuous conveyor 93 preferably embodying a continuous belt conveyor travelling in a longitudinal groove formed on the surface of the table 21 directly below the magazine casting, the upper portion of the belt being adapted to travel toward the forward end of the frame is designated by the arrow in 80 Figure 1.

85 Trained over the grooved gear 90 and a corresponding gear journaled at the opposed end of the frame is an endless chain conveyor 94 embodying a plurality of pivotally 90 connected links having their inner edges formed with arcuate recesses to permit rotary operation of the receivers 59. While the belt conveyor 93 is continuously operated, the chain conveyor 94 is intermittently 95 moved on the surface of the table, this being effected by the provision of transversely extending pins 95 arranged at periodic intervals, in the present embodiment at the end section of every fourth link, adaptable to 100 engage the lug 92 of the continuously rotatable drive gear 90. Thus, it will be noted that the chain conveyor is intermittently operated to relatively position a series of links in operative relation with respect to the magazine and receivers positioned thereunder. The links of the conveyor chain are formed to frictionally engage a match box, minus its cover, and move the box lengthwise on the table in a direction travelling 105 from the forward end to the rear end as denoted by the arrow in Figure 1 in reverse movement to the direction of travel of the belt conveyor which is adapted to return the filled containers to the forward starting position.

110 Thus, the conveyor drive gear 90 is continuously rotated, the lug 92 being in engagement with the pins of the endless chain during a part of its rotation and disengaged therefrom during the remainder of its movement. This operation is timed so that each operative movement of the drive gear will actuate the conveyor at a distance corresponding to four component links so that successive series of four containers are intermittently positioned in lateral opposed position with respect to the receivers and magazine.

In order that the chain conveyor 94 may be properly operated, arcuate guard members 94' are secured to the table and disposed about the outer segments of the conveyor gears 90, these members being adapted to frictionally engage the respective links of the chain so that the conveyor is resistibly actuated to provide a braking operation whereby the conveyor will be abruptly brought to rest when the driving lug 92 disengages the pins so as to properly position the links with respect to the receivers.

When each series of containers is properly positioned with relation to the rotatable receivers and the chain conveyor is at rest, the empty containers are laterally actuated in a simultaneous series from the chain links unto the receivers by a transferring mechanism. This mechanism embodies an angular bracket 96 formed with a depending flange 97 and a horizontal support flange 98. The vertical depending flange 97 is formed with a series of spaced slots adapted to clear the transverse vertical flanges of the chain links while the flange is slidably actuated through the links to transfer the containers unto the receivers. The upper horizontal flange 98 is formed with a pair of transverse sleeves 99 slidable in transversely projecting rods 100 secured on brackets 101.

The transferring member is periodically operated by mechanism embodying an outwardly projecting link 102 pivotally connected with the bracket 96 and with a downwardly depending lever 103 which is actuated by suitable cam structure. Thus, the transfer bracket 96 will be automatically actuated at periodic intervals in timed sequence with each cycle of operation so as to intermittently transfer the empty containers from the carrier or feed conveyor on to the receivers and simultaneously eject the filled containers from the receivers and deposit the same upon the return conveyor 93.

The various instrumentalities by which the successive functions are effected, are effected, are operated by a series of cam members fixed on the cam shaft 83. The transferring and magazine plate shifting mechanism are actuated by a circular plate cam 104 performing the function of a double cam, one face being formed with an elliptical cam groove 105 adapted to engage a follower attached to the lower end of the lever 103 so as to periodically actuate the transferring mechanism. The opposite face of this cam is formed with a continuous sinuous groove 106 formed to provide four uniformly spaced radially extending grooves to actuate the slidable magazine plate 37, this arrangement being adapted to actuate the magazine plate to perform four periodic movements during each rotation of the cam in timed sequence with the cycle of operation. The receivers 59 are intermittently oscillated through the

medium of a cam 107 formed to provide a pair of complementary laterally offset semi-circular sections the periphery of which is formed with a cam groove 108 whereby the member 67 is horizontally oscillated to reciprocate the rack 65. The rotatable stems 60 and receivers 59 formed on the upper ends thereof are periodically reciprocated in vertical movement by means of a cam 109 embodying a cam plate having its periphery formed to provide a plurality of, in the present embodiment four, equally spaced radial projections 109 adapted to elevate the lever 74 and oscillate the shaft 71 at proper intervals to elevate the receivers during the filling of the containers. Fixed to the rear end of the cam shaft 83 is a flanged cam plate 110, the outer edge of the flange being of uniform tortuous formation to constantly oscillate the agitating arms 29 so that the articles may drop unhindered into the containers.

In the operation of the machine, the containers embodying open topped receptacles are manually, or in any suitable manner, deposited upon the links of the conveyor chain 94 and fed or carried intermittently in successive series on to the intermediate portion of the table in lateral registration with the receivers 59. The conveyor 94 will then come to a period of rest. Immediately thereafter, the transferring bracket 96 will be laterally actuated to transfer the empty containers carried by the conveyor 94 on to a corresponding number of receivers 59. Subsequently, the magazine plate 37 will be moved laterally so that the pockets 38 containing a predetermined quantity of matches are arranged directly over the receivers. The receivers are then elevated and the delivery plates 44 separated so that matches are deposited in the container. This initial delivery is adapted to fill approximately one-half of the match containers and arrange the matches so that the heads thereof will be disposed at one end of the box. Immediately after this initial filling operation, the magazine plate is retracted so that the pockets 38 will receive a second filling from the magazine. Simultaneously with this action, the receivers 59 are rotated through an arc of 180°. The plate 37 is then extended for a second filling operation whereupon the matches will be reversibly positioned in successive layers.

After the completion of the filling operation, the plate 37 is again actuated to retracted position and the filled containers ejected from the receivers by a successive series of empty containers and the filled containers returned to a take-off position where the covers are manually or mechanically positioned on the boxes.

The sequence and mode of operation will be readily apparent with reference to Fig.

ure 11 wherein the essential functions and means for effecting the same are diagrammatically illustrated. The various co-operating steps of the machine will be readily noted from the examination of this figure wherein the cam actuating mechanisms are diagrammatically indicated together with the successively operating instrumentalities.

It is to be understood that the form of my invention herein shown and described is to be taken as a preferred example of the same, and that various changes as to the shape, size, and arrangement of parts may be resorted to without departing from the spirit of the invention or the scope of the subjoined claims.

Having thus fully described my invention, I claim:

1. A container filling machine comprising, in combination, means for moving a plurality of containers, a magazine arranged to fill the containers, means for transferring the containers from the said moving means into filling position relative to the magazine, and means for conveying the filled containers to a take-off position.

2. A container filling machine comprising, in combination, means for intermittently carrying a plurality of containers, a magazine adapted to deliver a predetermined quantity of material into the containers, means for relatively positioning the containers with respect to the magazine, means for laterally transferring the containers from filling position to an offset position, and means for conveying the filled containers to a take-off position.

3. A container filling machine comprising, in combination, a magazine, means for intermittently moving a plurality of containers to a position adjacent the magazine, means for transferring the containers from the said moving means to a filling position with respect to the magazine, and means for conveying the filled containers to a take-off position.

4. A container filling machine comprising a magazine, a conveyor for intermittently moving a plurality of containers in successive series to a position adjacent the magazine, means for transferring the containers from the said conveyor to a position for filling, means for filling the said containers, and means for carrying the filled containers to a removal position.

5. A container filling machine comprising a magazine, means for conveying a plurality of match containers in single file to position successive series of containers adjacent the magazine, means for laterally transferring the containers from the said conveyor to a filling position with respect to the magazine, means for depositing a quantity of matches in the said containers, and means for carrying the filled containers to a removal point.

6. In a container filling machine comprising a stationary magazine, means for intermittently conveying the empty containers in successive series to a position adjacent the said magazine, means for transferring the container to a filling position, and means for moving the containers to a removal position.

7. A container filling machine comprising a magazine, means for carrying a plurality of containers adjacent the magazine, means for transferring the containers from the carrying means into position for filling, and means for conveying the filled containers to a position for removal.

8. A container filling machine comprising a fixed magazine, means for carrying a plurality of containers to a position adjacent the magazine, means for transferring the containers to filling position in successive series, and means for carrying the filled containers to a removal position.

9. A match-box filling machine comprising a magazine, means for delivering a plurality of containers to a position adjacent the magazine, means for intermittently transferring the containers in successive series from the said delivery mean into filling position, and means for moving the filled containers to a position for removal.

10. A filling machine comprising, in combination, a magazine, means for intermittently moving a plurality of match boxes to a position adjacent the magazine, means for intermittently transferring the boxes in successive series from the said moving means to filling position with respect to the magazine, means for depositing matches in the said boxes, and means for carrying the filled boxes to a take-off position.

11. In a match-box filling machine comprising a fixed magazine, means for intermittently carrying a plurality of boxes to a position adjacent the magazine, means for intermittently transferring the boxes in successive series from the said carrying means to a filling position with respect to the magazine, means for filling the said boxes, and means for removing the said filled boxes.

12. A container filling machine comprising a magazine, means for intermittently carrying a plurality of containers adjacent the magazine, means for holding the containers during the filling thereof, means for transferring the containers from the carrying means on to the said holding means, means for filling the said containers, and means for removing the said filled containers.

13. A container filling machine comprising a fixed magazine, means for relatively positioning a plurality of containers with respect to the said magazine, means for holding the containers during the filling thereof disposed at one side of the carrying means, means for transferring the containers from

- the carrying means on to the said holding means and simultaneously ejecting the filled containers from the holding means, and means for removing the filled containers. 65
- 5 14. A container filling machine comprising a magazine, means for carrying a plurality of containers adjacent the magazine, container receiving means mounted adjacent the carrying means and adapted for 10 oscillating movement, means for transferring the containers on to the said receiving means, means for filling the containers with successive layers of reversibly positioned articles, and means for removing the filled containers. 70
- 15 15. In a match-box filling machine comprising a magazine, means for carrying a plurality of containers to a position adjacent the magazine, means for holding the containers in filling position adjacent the 20 magazine adapted to be reversibly rotated and periodically elevated, means for depositing successive layers of matches in reversed positions in the containers, and means for removing the filled containers. 75
- 25 16. In a match-box filling machine including a magazine, means for intermittently carrying a plurality of boxes to a position adjacent the magazine, means for holding the said boxes in filling position, means for 30 transferring the boxes from the said carrying means on to the said holding means, means for filling the boxes with successive reverse layers of matches, and means for removing the filled containers. 80
- 35 17. A match-box filling machine comprising a magazine, means for moving a plurality of boxes in successive series to a position adjacent the magazine, a plurality of receivers arranged adjacent the magazine 40 adapted for alternate oscillating and reciprocating movement, means for transferring the boxes from the moving means on to the said receiving means, means for filling the said boxes, and means for removing the filled boxes. 85
- 45 18. A match-box filling machine comprising, in combination, a magazine, means for intermittently delivering a predetermined quantity of matches from the said magazine, means for intermittently carrying a plurality of boxes adjacent the magazine, receiving 50 means arranged adjacent the magazine adapted to reverse the position of the container during the filling operation, means for transferring the boxes from the carrying means on to the receiving means, and means for removing the filled boxes. 90
- 55 19. A match-box filling machine comprising, in combination, a magazine having means for intermittently depositing predetermined quantities of matches at laterally arranged filling positions, means for constantly agitating the matches in the said magazine, means for relatively positioning 55 the boxes with respect to the magazine, and means for removing the filled boxes. 95
- 60 20. In a match-box filling machine including a magazine, means associated with the magazine for intermittently carrying a predetermined quantity of matches to an offset position, means for releasing the said matches and depositing the same in boxes, means for relatively positioning empty boxes with respect to the magazine and filling means, and means for removing the said filled boxes. 100
- 65 21. A match-box filling machine comprising, in combination, a magazine, a conveyor adapted to intermittently position a plurality of boxes relative to the magazine, a plurality of receivers arranged adjacent the magazine operable to reverse the position of the boxes during the filling operation, transferring means adapted to transfer the boxes in successive series from the conveyor to the receivers, and means for conveying the filled boxes to a removal position. 105
- 70 22. A match-box filling machine comprising, in combination, a support frame, a magazine casing supported on the frame, means for delivering a quantity of matches intermittently from the said magazine, a conveyor adapted to carry a plurality of boxes in intermittent successive series, a plurality of receivers disposed below and adjacent to the magazine adapted to reversibly rotate the boxes and periodically elevate the same for filling, a transferring means adapted to intermittently transfer the boxes in successive series, from the conveyor on to the receivers and simultaneously eject the filled containers from the receivers, and means for carrying away the filled containers. 110
- 75 23. In a match-box filling machine including a magazine, a plate formed with a plurality of receiving pockets movably associated with the bottom of the magazine and adapted to carry a plurality of matches from the magazine to a laterally offset delivery position, means for automatically releasing the matches from the pockets during the rest periods of the plate, means for relatively positioning a plurality of boxes in successive series with respect to the magazine and slidable plate, and means for removing the filled boxes. 115
- 80 24. A match-box filling machine comprising, in combination, a support frame, a magazine supported in elevated position on the frame, means for periodically delivering a quantity of matches from the said magazine, means for relatively positioning a plurality of boxes in successive series with respect to the magazine, means for reversibly oscillating the boxes to arrange the matches in successive reversed layers, and mechanism for removing the filled boxes. 120
- 85 25. In a match-box filling machine includ- 125

ing a support frame, a magazine supported on the frame, means associated with the magazine for intermittently delivering a predetermined quantity of matches from the
5 magazine, box receiving members positioned adjacent the magazine and adapted to reversibly rotate the boxes and alternately elevate the same for filling, conveying means

adapted to relatively position the boxes with respect to the magazine, and mechanism for 10 automatically carrying away the filled boxes.

In witness whereof I have hereunto set my hand.

KARL BERGSTRÖM.
